US00D670811S

(12) **United States Design Patent**
Fukuzawa

(10) **Patent No.:** **US D670,811 S**
(45) **Date of Patent:** **** Nov. 13, 2012**

(54) **BLOOD GLUCOSE LEVEL MEASURING DEVICE**

7,841,993 B2 * 11/2010 Kojima et al. 600/583
D633,814 S * 3/2011 Nishiyama D10/81
2011/0034786 A1 * 2/2011 Cadio et al. 600/316

(75) Inventor: **Masahiro Fukuzawa**, Kyoto (JP)
